DESIGN FOR AN ELECTRIC BROILER

Joseph M. Majewski, Jr., Kansas City, Mo., assignor to Foster L. Talge, Kansas City, Mo., doing business as Rival Manufacturing Company

Application May 17, 1940, Serial No. 92,422

Term of patent 14 years

To all whom it may concern:

Be it known that I, Joseph M. Majewski, Jr., a citizen of the United States, residing at Kansas City, in the county of Jackson and State of Missouri, have invented a new, original, and ornamental Design for an Electric Broiler, of which the following is a specification, reference being had to the accompanying drawing, forming part thereof, in which:

Fig. 1 is a perspective view of an electric broiler in open position, showing my new design.

Fig. 2 is a top plan view of the electric broiler shown in Fig. 1, in closed position.

Fig. 3 is a side elevation of the electric broiler shown in Fig. 1, in closed position.

I claim:

The ornamental design for an electric broiler, substantially as shown.
